UNITED STATES PATENT OFFICE.

JEAN F. WEBB, OF DENVER, COLORADO.

ELECTRIC SEMAPHORE.

No. 829,132.

Specification of Letters Patent.

Patented Aug. 21, 1906.

Application filed August 22, 1905. Renewed June 25, 1906. Serial No. 323,360.

To all whom it may concern:

Be it known that I, JEAN F. WEBB, residing at Denver, in the county of Denver and State of Colorado, have invented certain new and useful Improvements in Electric Semaphores, of which the following is a specification.

My invention relates to certain new and useful improvements in electric semaphores for use in connection with railway systems, and it more particularly relates to that class of semaphore mechanisms in which locking devices are provided for holding the semaphore-arm in its normal or safety position and in which electromagnetically-operated means are provided for releasing said locking devices to permit the semaphore being moved to its danger position and at the same time operate a signal in the tower-house to inform the operator that the signal has been properly set or moved to its danger position.

Primarily my invention has for its object to provide a semaphore of this class of a very simple construction which can be easily and cheaply manufactured and which will readily and effectively serve its intended purposes. Again, the invention seeks to provide a mechanism of this character in which all the operating parts are so arranged that ready access may be had thereto whenever it may be found desirable to inspect said parts or insert or remove a signal-lamp.

In its generic nature my invention comprises suitable supports or standards upon which a semaphore-arm is pivotally mounted and upon which locking devices are mounted for coöperating with the semaphore-arm to hold it in its normal or safety position. Upon the standards I also mount electro-magnetic locking devices, and circuit-closing mechanism for operating supplemental signals in the tower-house to indicate the position of the semaphore parts. Means are also provided whereby the locking mechanism is electromagnetically released at times when desired to allow the semaphore-arm to move to its danger-indicating position.

My present invention also includes a casing in which a signal-lamp is mounted and shutter devices for cutting off light-rays emanating from the signal-light when the semaphore is in its safety position and for exposing the signal-light when the semaphore is in its danger-indicating position, said shutter devices being controlled by the movement of the semaphore-blade.

With other objects in view than have heretofore been enumerated the invention also includes certain novel construction, combination, and arrangement of parts, all of which will be first described in detail, and then specifically pointed out in the appended claims, reference being had to the accompanying drawings, in which—

Figure 1 is a perspective view of my invention. Fig. 2 is a similar view, the casing being removed. Fig. 3 is a side elevation of my invention, the casing being shown in section and the parts being in their normal or "safety" position. Fig. 4 is a similar view, the parts being shown in their danger-indicating position, the signal-lantern being shown in dotted lines. Fig. 5 is an end elevation of the parts shown in Fig. 4, the casing being shown in section. Fig. 6 is a detail section on the line 6 6 of Fig. 4. Fig. 7 is a diagrammatic view showing the arrangement of electric circuits when the parts are in their normal or safety position, as shown in Fig. 3. Fig. 8 is a view similar to Fig. 7 showing the arrangement of the electric circuits when the parts are in their danger-indicating position, as shown in Fig. 4.

Referring now to the accompanying drawings, in which like numerals of reference indicate like parts in all of the figures, it will be seen that secured to the supporting-post 2 by lag-screws 3 3 or otherwise is a pair of iron supports 1^a 1^b, which extend vertically upward above the post and which supports carry the operative parts of my semaphore mechanism. At the upper ends the supports 1^a 1^b are secured together by the spacing-rod 4, whose ends 4^a are threaded to pass through apertures 1^c 1^c in the supports 1^a 1^b and which receive the securing-nuts 4^b 4^b, the rod 4 being provided with shoulders 4^c 4^c to abut the supports 1^a 1^b, as shown.

5 designates a shaft, preferably of steel, which is mounted to turn in bearing-apertures 1^d 1^d in the supports 1^a 1^b, and this shaft 5 has a reduced portion 5^b, forming a shoulder 5^c to abut the support 1^a, which reduced portion has its end threaded to receive the washer 5^d and the securing-nut 5^e, as clearly shown in Fig. 5. The reduced portion 5^b on shaft 5 has its extended end threaded to receive the securing-nuts 5^f 5^f, by means of which the arm 6 is secured to the shaft. The arm 6 has its free end provided with a weight 7 and is formed with a notch 6^a to coöperate with the spring-stop 54, secured

by rivets 41 41 to the support 1^a in a manner presently more fully explained. The semaphore-blade 5^a is secured to the other end of the shaft 5.

5 8 designates what I term the "trip-rod," which has its upper end 8^a of reduced diameter to pass through an aperture 5^c in the rod 5, to which it is secured by a nut 8^b. The free end of the rod 8 is beveled, as at 8^c, to co-operate with the revolving trip-wheel 9. The wheel 9 is formed of a plurality of radial arms or spokes 9^b 9^b and a weighted portion 9^c, and the said wheel 9 has a shaft 9^a, provided with conical bearing ends 9^d 9^d to coöperate with the bearing ends 42^b of the bearing-screws 42^a, which are secured in the supports 1^a 1^b. The screws 42^a have check-nuts 42^c to hold them to their adjusted positions.

Secured to the supports 1^a 1^b below the shaft 9^a by rivets 41 41 or otherwise are bracket-plates 35^a 35^b, in which bearing-screws 43^a 43^a are screwed. The screws 43^a have their bearing ends countersunk, as at 43^b, to receive the conical bearing ends of a rod 11, which carries a trip-lever 10, whose heel 10^a is normally adapted to engage one of the arms or spokes 9^b of the wheel 9 to hold the same from turning. At its other end the trip-lever 10 has an armature 12, which coöperates with an electromagnet 13 of the horse-shoe type, the magnet 13 being mounted on a U-shaped bracket 36, which is adjustably secured to the bracket-plate 35^b by set-screws 39^a 39^a, which pass through slots 38^a in the bracket 36. 37 designates a set-screw adjustably held by the bracket 36, against which the trip-lever rests when in its normal wheel-engaging position.

Secured to the support 1^b by binding-screws 17^c 17^d, which pass through insulating-bushings 16^c 16^d, is a pair of contact-plates 15^c 15^d, which are normally held out of contact with one another, but which when engaged by the trip-lever 10 when in its wheel-releasing position are brought into contact with one another to close a signal-circuit, as will be hereinafter more fully explained. The contact-plates 15^c 15^d are what I shall hereinafter term the "trip-lever circuit-closers."

50 Secured adjacent the shaft 5 to the support 1^b by binding-screws 17^a 17^b, which are held in insulating-bushings 16^a 16^b, is a second pair of spring contact-plates 15^a 15^b, which also are normally out of contact with one another and which at times are adapted to be engaged and moved into contact with one another by a cam 14, held on the shaft 5 by a screw 44, as shown.

23 designates a pitman vertically movable in the bearing-apertures of plates 33^a 33^b, which are secured to the support 1^a by rivets 41 or otherwise. The pitman 23 has a right-angled portion 23^a, adapted to be engaged by the lifting-rod 21, which is secured to the shaft 5 by a nut 21^a, and the rod 21 has a fin-

ger or stop 22 to prevent the portion 23^a of the pitman 23 slipping when engaged by the rod 21 in a manner presently more fully understood.

A bracket-plate 34 is riveted or otherwise secured to the support 1^a below the plates 33^a and 33^b.

26^a 26^b are stud portions secured to the bracket-plate 34 by nuts 26. Fulcrumed on the studs 26^a 26^b are rocking bars 25^a 25^b, each of which is provided with a slot 27^a 27^b and each of which at its outer ends carry blinds or shutters 24^a 24^b, for a purpose presently explained. The bars 25^a and 25^b cross one another and receive a lug 23^b of the pitman 23 in their slots 27^a 27^b, so that when the pitman 23 is raised or lowered the bars 25^a and 25^b and the blinds 24^a 24^b will be moved in unison.

28 designates a railway-lantern of the usual type, having the usual red or "danger" bull's-eyes 29^a 29^b and having sockets 32^a 32^b to fit over pins 31^a 31^b on the post 2 to hold the lugs in place. The oil-receptacle of the lamp with burner attached is designated by 30.

Secured to the support 1^b is a stop 40, which limits the return movement of the trip-rod 8.

46 designates a casing for inclosing the operating parts of the apparatus, which casing has top, side, and bottom plates, as shown. The ends of my casing 46 are closed by doors 48^a 48^b, hinged to the casing-top, as at 49^a 49^a, provided with glass windows 50^a 50^b, disposed in alinement with the bull's-eyes 29^a 29^b in the lantern 28.

51^a 51^b designate hasps secured to the doors 48^a 48^b, which coöperate with the staples 52^a 52^b, secured to the casing-bottom, locks 53^a 53^b being provided to lock the doors 51^a 51^b when closed.

55 designates the main operating line-wire, which is shown connected with the electromagnet 13 by the lead 13^a, and the magnet 13 is grounded through a lead 13^b.

56 designates the main signaling line-wire, which connects to the binding-post 17^a of the semaphore-shaft circuit-closer, the binding-post 17^b of which connects to the binding-post 17^c of the trip-lever circuit-closer by a wire 18, while the other binding-post 17^d of the trip-lever circuit-closer is grounded through a wire 20.

60 designates a switch at the operator's tower, which has one terminal 58 connected to the line-wire 55, while its other terminal 59 connects, through a battery 57, to the ground. The line-wire 56 connects, through switch 62, with a signal 61 in the operator's tower, which signal in turn connects to supplemental battery 63, which battery 63 is also grounded, as shown.

Operation: Assume the parts to be in their safety position, as shown in Fig. 3. The

trip-rod engages the upper spoke of the revolving trip-wheel 9, while the lower spoke of the trip-wheel 9 is engaged by the heel of the trip-lever 10. The trip-lever 10 therefore holds the wheel 9 from revolving, which in turn holds the semaphore-shaft from turning on its axis and maintains the semaphore in its safety position. The bull's-eyes 29^a 29^b are screened by the blind 24^a, so that no light 5 shows from the casing - windows 50^a 50^b. When it is desired to signal a train by throwing the semaphore-blade into its warning or danger position or by showing the red "danger" light, the operator in the signal-tower 10 closes the main-line switch, thus sending a current over the main-line wire to energize a 15 the electromagnet 13, which thereupon attracts the armature 12 to disengage the heel of the trip-lever from the lower spoke of the 20 revolving wheel 9. As soon as the trip-lever 10 is disengaged from the wheel 9, the weight-arm 6 will drop of its own weight to raise the semaphore-blade to its danger-indicating position, the weighted portion of the wheel 9 25 serving to hold the wheel 9 with its spokes in a position to be engaged by the rod 8 when the semaphore-blade is reset to its safety position, in a manner presently more fully understood. The turning of the semaphore-shaft 5 raises the lifting-rod 21, which in its 30 movement engages the upper horizontal extension 23^a of the pitman 23 and lifts the said pitman, the pin 24 keeping the right-angled extension 23^a from slipping backward on the 35 lifting-rod 21. As the rod 23 is raised the bars 25^a 25^b are swung on their pivots 26^a 26^b to raise the blinds 24^a 24^b to permit a red light or danger-signal from the lantern to be seen through the windows 50^a 50^b of the casing. The raising of the blinds 24^a 24^b uncovers 40 the bull's-eyes 29^a 29^b in a manner clearly understood by reference to the drawings. When the trip-releasing magnet 13 moves the armature 12 to move the heel of the trip-lever 10 out of engagement with the lower 45 spoke of the wheel 9, the trip-lever engages the contact-spring 15^c and presses it against the contact-spring 15^d, thus closing the "return - signal" circuit at that point. The 50 turning of the semaphore-shaft 5 turns the cam 14 attached thereto, so that the cam 14 engages the spring 15^a and presses it against the spring-contact 15^b, closing the circuit of the return-signal at that point, thus making 55 the circuit for the return-signal complete, so far as the semaphore is concerned, to permit the electric current from the signaling-battery to operate the return-signal at the tower-station. The parts are now in the position 60 shown in Fig. 4. When the current for the trip-releasing magnet 13 is turned off at the operator's station, the armature 12 drops over from the trip-releasing magnet 13, raising the heel of the trip-lever 10 off of the 65 spring 15^c, thus breaking the return-signal

circuit at that point and also leaving the trip-lever 10 free to engage the spoke of the revolving trip - wheel 9 as the semaphore is being reset. To reset the semaphore, it is only necessary to turn the weighted arm 70 6 back to its horizontal position, which brings the rod 8 back to the wheel - engaging position. As the rod 8 is brought back to its normal position, the free end thereof will engage the spoke of the revolving 75 trip - wheel 9, turning the said wheel until the heel of the trip-lever 10 again engages the lower spoke of the trip-wheel 9, thus locking the semaphore to its normal position again. The revolving trip-wheel 9 has a weighted 80 section, as before stated, and after the trip has been released the weighted section serves to stop the wheel in such a position that one spoke of the wheel is always in the proper position to be engaged by the trip-rod 8 as the 85 semaphore is being reset to push the wheel around until another spoke underneath is pushed past the heel of the trip-lever 10, so that it will be engaged by the said heel of the trip-lever 10 and lock the semaphore in its 90 normal or safety position after the trip-rod 8 is in engagement with the stop 40 and is permitted to engage the upper spoke of the revolving trip-wheel 9. As the weighted arm 95 6 is raised after the parts have been in their danger-indicating position the cam 14 is disengaged from the spring 15^a, which spring is released, thus breaking the return-signal circuit at that point. The lifting-rod 21 is also 100 drawn away from engagement with the pitman 23, permitting the rocking bars 25^a 25^b, with their attached blinds 24^a 24^b, to gravitate to their normal position and cut off the light from the bull's-eyes 29^a 29^b of the lantern 28. When the semaphore is in 105 its danger-indicating position and the arm 6 is dropped to its vertical position, the notch in its lower end will engage the spring 54, thus stopping the weight at the proper point and preventing it from oscillating. 110

From the foregoing description, taken in connection with the accompanying drawings, it is thought that the complete construction, operation, and many advantages of my invention will be readily understood by those skilled in the art to which it appertains. 115

Having thus described my invention, what I claim, and desire to secure by Letters Patent, is—

1. A semaphore mechanism comprising 120 supports, a shaft fulcrumed thereon, a counterweight and a semaphore-blade secured to the shaft, means directly connected to said shaft for locking said shaft from rotation, electromagnetic trip devices for releasing 125 said locking means, and a circuit-closer controlled by said trip devices for closing an electric signaling-circuit, substantially as shown and described. 130

2. A semaphore mechanism comprising 130

supports, a shaft fulcrumed thereon, a counterweight and a semaphore-blade secured to the shaft, means for locking said shaft from rotation, electromagnetic trip devices for releasing said locking means, a circuit-closer controlled by said trip devices, and a second circuit-closer controlled by said shaft for closing an electric signaling-circuit.

3. A semaphore mechanism comprising supports, a shaft fulcrumed thereon, a counterweight and a semaphore-blade secured to the shaft, means for locking said shaft from rotation, electromagnetic trip devices for releasing said locking means, a circuit-closer controlled by said trip devices, a second circuit-closer controlled by said shaft for closing an electric signaling-circuit, and a casing for the whole.

4. A mechanism of the class described comprising supports, a shaft rotatable therein, means for locking said shaft from rotation, electromagnetic devices for releasing said locking means, a signal-lantern, shutter devices, means carried by the shaft for controlling the shutter devices to cut off the light from the lantern, and means for turning said shaft when unlocked to withdraw the shutter devices from the path of the light-rays from the lantern.

5. A mechanism of the class described comprising supports, a shaft rotatable therein, means for locking said shaft from rotation, electromagnetic devices for releasing said locking means, a signal-lantern, shutter devices controlled by the movement of the shaft for cutting off the light from the lantern, means for turning said shaft when unlocked to withdraw the shutter devices from the path of the light-rays from the lantern, and a casing for the whole having windows for the passage of the light-rays from the lantern.

6. A mechanism of the class described comprising supports, a shaft rotatable therein, means for locking said shaft from rotation, electromagnetic devices for releasing said locking means, a signal-lantern, shutter devices controlled by the movement of the shaft for cutting off the light from the lantern, means for turning said shaft when unlocked to withdraw the shutter devices from the path of the light-rays from the lantern, and a circuit-closer controlled by the shaft for closing an electric circuit when the shaft is turned.

7. A mechanism of the class described comprising supports, a shaft rotatable therein, means for locking said shaft from rotation, electromagnetic devices for releasing said locking means, a signal-lantern, shutter devices controlled by the movement of the shaft for cutting off the light from the lantern, and means for turning said shaft when unlocked to withdraw the shutter devices from the path of the light-rays from the lan-

tern, a circuit-closer controlled by the shaft for closing an electric circuit when the shaft is turned, and a housing for the whole having windows registering with the bull's-eyes of the lantern.

8. A signaling mechanism comprising a support, a lantern held therein, means for normally intercepting the light-rays emanating from the lantern, means for withdrawing said intercepting means at times, means for normally rendering the said withdrawing means inoperative, electromagnetic devices for releasing said last-named means, and circuit-closers controlled by said releasing devices for closing a supplemental electric signaling-circuit.

9. A signaling mechanism comprising a support, a lantern held therein, means for normally intercepting the light-rays emanating from the lantern, means for withdrawing said intercepting means at times, means for normally rendering the said withdrawing means inoperative, electromagnetic devices for releasing said last-named means, circuit-closers controlled by said releasing devices for closing a supplemental electric signaling-circuit, and a casing for the whole having windows through which the light-rays are adapted to pass.

10. In a semaphore mechanism, supports, a shaft rotatable therein, a semaphore-blade secured to the shaft, a rod secured to the shaft, a rotatable trip-wheel for co-operating with said rod to hold the shaft from turning, a trip-lever for engaging the trip-wheel to hold the same from rotation, an electromagnet for releasing said trip-lever from said wheel, and means for rotating said shaft when said wheel is released.

11. In a semaphore mechanism supports, a shaft rotatable therein, a semaphore-blade secured to the shaft, a rod secured to the shaft, a rotatable trip-wheel for co-operating with said rod to hold the shaft from turning, a trip-lever for engaging the trip-wheel to hold the same from rotation, an electromagnet for releasing said trip-lever from said wheel, means for rotating said shaft when said wheel is released, and a housing for the whole.

12. In a signaling mechanism, supports, a shaft rotatable therein, a lantern having bull's-eyes, shutter devices for said lantern, means controlled by the movement of said shaft for operating said shutter devices, a rod secured to the shaft, a rotatable trip-wheel for co-operating with said rod to hold the shaft from turning, a trip-lever for engaging the trip-wheel to hold the same from rotation, an electromagnet for releasing said trip-lever from said wheel and means for rotating said shaft when said wheel is released.

13. In a signaling mechanism, supports, a shaft rotatable therein, a lantern having bull's-eyes, shutter devices for said lantern,

means controlled by the movement of said shaft for operating said shutter devices, a rod secured to the shaft, a rotatable trip-wheel for coöperating with said rod to hold the shaft from turning, a trip-lever for engaging the trip-wheel to hold the same from rotation, an electromagnet for releasing said trip-lever from said wheel, means for rotating said shaft when said wheel is released, a circuit-closer controlled by the movement of said shaft, a circuit-closer controlled by said trip-lever, and a signaling-circuit common to both circuit-closers.

14. In a signaling mechanism, supports, a shaft rotatable therein, a semaphore-blade secured to the shaft, a lantern having bull's-eyes, shutter devices for said lantern, adapted to close over the bull's-eyes, means controlled by the movement of said shaft for actuating said shutter devices, a rod secured to the shaft, a rotatable trip-wheel for coöperating with said rod to hold the shaft from turning, a trip-lever for engaging the trip-wheel to hold the same from rotation, an electromagnet for releasing said trip-lever from said wheel, and means for rotating said shaft when said wheel is released.

15. In a signaling mechanism, supports, a shaft rotatable therein, a semaphore-blade secured to the shaft, a lantern having bull's-eyes, shutter devices for said lantern, adapted to close over the bull's-eyes, means controlled by the movement of said shaft for actuating said shutter devices, a rod secured to the shaft, a rotatable trip-wheel for coöperating with said rod to hold the shaft from turning, a trip-lever for engaging the trip-wheel to hold the same from rotation, an electromagnet for releasing said trip-lever from said wheel, means for rotating said shaft when said wheel is released, circuit-closers controlled by the movement of said shaft and said trip-lever, a casing for the whole, and a signaling-circuit common to both circuit-closers.

16. In a signaling mechanism, supports, a signal-lantern having diametrically opposite bull's-eyes held on said support, shutter devices for each of said lantern bull's-eyes, means for operating said shutter devices in unison, means for locking said operating means, and electromagnetic devices for releasing said locking means.

17. In a signaling mechanism, supports, a signal-lantern having bull's-eyes held on said supports, shutter devices for said lantern, means for operating said shutter devices, means for locking said operating means, electromagnet devices for releasing said locking means, and an electric indicating-circuit controlled by said releasing devices.

18. In an apparatus of the class described, a rotatable shaft, an arm secured thereto, a rotatable trip-wheel for engaging the free end of said arm to hold the shaft from rotation, a

latch for engaging said trip-wheel to hold it from rotation, an electromagnet for releasing said latch from said wheel, and means for rotating said shaft when the latch is released.

19. In an apparatus of the class described, a rotatable shaft, an arm secured thereto, a rotatable trip-wheel for engaging the free end of the arm, a latch for engaging said wheel to hold it from rotation, an electromagnet for releasing said latch from said wheel, means for turning said wheel when released to disengage said arm therefrom.

20. In an apparatus of the class described, a rotatable shaft, an arm secured thereto, a rotatable trip-wheel for engaging the free end of the arm, a latch for engaging said wheel to hold it from rotation, an electromagnet for releasing said latch from said wheel, means for turning said wheel when released to disengage said arm therefrom, and signaling devices coöperatively connected with said shaft and controlled thereby.

21. In an apparatus of the class described, a rotatable shaft, an arm secured thereto, a rotatable trip-wheel for engaging the free end of the arm, a latch for engaging said wheel to hold it from rotation, an electromagnet for releasing said latch from said wheel, means for turning said wheel when released to disengage said arm therefrom, signaling devices coöperatively connected with said shaft and controlled thereby, and a housing for the whole.

22. In a signaling mechanism, supports, a shaft rotatable therein, a semaphore-blade and a weighted arm secured to said shaft, a trip-rod secured to the shaft, a rotatable trip-wheel adapted to be engaged by said trip-rod at times, electromagnetically-controlled latch devices for holding said wheel from rotation, a lantern held on said supports, said lantern having bull's-eyes, a pair of bars each fulcrumed at one end and having slots, shutters carried by said bars at the free ends for closing over said bull's-eyes, a pitman having a lug for entering the slots in the bars, and a lifting-rod secured to said shaft for lifting said pitman.

23. In a signaling mechanism, supports, a shaft rotatable therein, a semaphore-blade and a weight-arm secured to said shaft, a trip-rod secured to the shaft, a rotatable trip-wheel having radial spokes adapted to be engaged by said trip-rod at times, electromagnetically-controlled latch devices for holding said wheel from rotation, a lantern held on said supports, said lantern having bull's-eyes, a pair of bars each fulcrumed at one end and having slots, shutters carried by said bars at the free ends for closing over said bull's-eyes, a pitman having a lug for entering the slots of the bars, and a lifting-rod secured to said shaft for lifting said pitman.

24. In a signaling mechanism, supports, a shaft rotatable therein, a semaphore-blade

and a weighted arm secured to said shaft, a trip-rod secured to the shaft, a rotatable trip-wheel adapted to be engaged by said trip-rod at times, electromagnetically-controlled latch devices for holding said wheel from rotation, a lantern held on said supports, said lantern having bull's-eyes, a pair of bars each fulcrumed at one end and having slots, shutters carried by said bars at the free end for closing over said bull's-eyes, a pitman having a lug for entering the slots in the bars, a lifting-rod secured to said shaft for lifting said pitman, and a housing for the whole.

25. In a signaling mechanism, supports, a shaft rotatable therein, a semaphore-blade and a weighted arm secured to said shaft, a trip-rod secured to the shaft, a rotatable trip-wheel adapted to be engaged by said trip-rod at times, electromagnetically-controlled latch devices for holding said wheel from rotation, a lantern held on said supports, said lantern having bull's-eyes, a pair of bars each fulcrumed at one end and having slots, shutters carried by said bars at the free ends for closing over said bull's-eyes, a pitman having a lug for entering the slots in the bars, a lifting-rod secured to said shaft for lifting said pitman, a circuit-closer controlled by the movement of said shaft and a second circuit-closer controlled by the movement of said latch device for closing the indicating-circuit, and a housing for the whole, said housing having doors at the ends and said doors having windows for registering with the lantern bull's-eyes.

JEAN F. WEBB.
